UNITED STATES PATENT OFFICE.

ARCHIBALD M. EWART, OF BARBERTON, OHIO.

TALKING-MACHINE CABINET.

1,121,238.

Specification of Letters Patent. Patented Dec. 15, 1914.

Application filed June 8, 1914. Serial No. 843,711.

To all whom it may concern:

Be it known that I, ARCHIBALD M. EWART, a citizen of the United States, residing at Barberton, in the county of Summit and State of Ohio, have invented certain new and useful Improvements in Talking-Machine Cabinets, of which the following is a specification.

This invention relates to improvements in talking machine cabinets and more particularly to a disk record handling device.

One of the objects of my invention is to provide a disk record storing compartment from which any particular record may be chosen by the operation of a key or finger button positioned in the upper compartment of the instrument.

An other object of my invention is to provide such a device in which a plurality of record selecting keys are positioned conveniently in the top of the cabinet so that the operator may select the record which he desires to play without stooping over and scrutinizing the numbers such as are usually provided upon the individual slots of the record receiving rack.

Other and further objects will become apparent to those skilled in the art from a consideration of the following description and drawings, wherein;

Figure 1 is a plan view of my improved apparatus with the lid raised. Fig. 2 is a front elevation, parts being broken away. Fig. 3 is a vertical, sectional view through one end of the cabinet. Fig. 4 is an enlarged sectional view similar to that of Fig. 3, parts being broken away. Fig. 5 is a transverse, sectional view on line 5—5 of Fig. 3. Fig. 6 is an enlarged view of the record index, and Fig. 7 is a transverse, sectional view on line 7—7 of Fig. 6.

Referring to the drawings, it will be apparent that the casing structure is divided in three separate compartments. The lower compartment indicated by the numeral 10 serves as storage space for the record disks, the compartment directly above that, indicated by the numeral 11, receives the motor and horn, while the upper compartment 12 provided with a lid 13 carries the motor driven record table 14 and reproducer arm 15.

In the record storing compartment 10 I have provided a rack comprising the horizontal transverse frame members 16 and 17 between which are positioned a plurality of

thin partitions 18 spaced apart a distance slightly greater than the thickness of a record. At the rear a stop bar 19 extends across the back of the frame to hold the records from running through the rear of the slots formed by the partitions 18. The upper surface of the lower frame member 17 is inclined rearwardly so that a record when placed on the forward edge thereof will naturally roll back into its proper position. A drawer 20 is slidably mounted beneath the lower frame member 17 for receiving extra records, tools or the like, and the compartment 10 is closed by the two hinged doors 21.

So far the description of my apparatus follows closely the construction which is standard of cabinet type talking machines. In such machines, however, it is customary to place small letters or numbers adjacent each of the slots formed by the partitions 18 in order to identify the record for which the slot is reserved by consultation of a book or card having index spaces corresponding with the numbers or letters on the slots. It is thus necessary for the operator to bend nearly double to scrutinize the characters adjacent the slots since the record receiving slots are always positioned in the lower part of the cabinet. It is to obviate this inconvenience, as well as to insure the withdrawal of the record desired, that I have devised the following structure.

Each of the slots formed by the partitions 18 is provided with a pusher rod having a horizontal section 22 positioned at a height approximately registering with the top of the disk record extending forwardly into the slot a distance somewhat less than one quarter of its depth, and then angling downwardly and rearwardly as at 22' at approximately 45 degrees to the horizontal section. The lower end is then bent vertically to engage with an opening in a plate 23 secured to the rear wall of the compartment 10. At the rear end of the horizontal section 22 the rod extends vertically as at 24, upwardly, through the compartment 11, up into the compartment 12, terminating in a button or key 24'. A guiding block 25 is secured at the rear lower corner of the compartment 12 and provided with a plurality of vertical openings, through which the rod 24 extends.

Coil springs 26 surround each of the rods 24 abutting at their lower ends against a guide plate 27 and at their upper ends against keys 28, passing through or secured

to the rod 24. The action of the spring is to normally hold the vertical rod 24 together with the pusher parts 22, 22' upward into the position shown in Fig. 3.

5 An index receiving frame comprising vertical side bars 29—29 and the removable paper slips 30 are attached to the inner surface of the lid 13, for ready reference. A number is positioned opposite each of the 10 removable slips 30 corresponding to the numbers on the key 24'.

To select a particular record, the operator looks up on the index the name of the record, observes the number opposite the name, 15 and then depresses the key bearing that number. Depression of the key moves downwardly the pushed rod 24 and parts 22—22' thereof throwing forward the disk record contained in that particular slot to 20 a position where it is easily grasped and removed.

Having described my invention, what I claim is:—

1. A disk record selecting device comprising a rack having a plurality of record receiving slots therein, open at their front ends for insertion and removal of disk records, and a vertically reciprocable rod for each slot positioned at the rear of said rack,

30 said rod having a cam shaped extension projecting into a disk holding slot and adapted on downward movement thereof to engage said disk and slide same forward in its slot and project a portion thereof beyond the front face of the rack.

35 2. A disk record selecting device comprising a rack having a plurality of record receiving slots therein, open at their front ends for insertion and removal of disk records, a vertically reciprocable rod for each 40 slot positioned at the rear of said slot, each said rod having a cam shaped extension projecting into a disk holding slot adapted on downward movement thereof to engage said disk and slide the same forward in a slot 45 and project a portion thereof beyond the front face of the rack, guides for the upper and lower ends of said rod, and resilient means for normally holding said rod in its uppermost position.

50 In testimony whereof I hereunto set my hand in the presence of two subscribing witnesses.

ARCHIBALD M. EWART.
